ELECTRICALLY HEATED STERILIZING AND
COOLING APPARATUS ADAPTED TO BE
USED AS AN ICE BOX

Manfred Abraham, Berlin, Germany

Application November 7, 1934, Serial No. 751,909
In Germany October 5, 1933

6 Claims. (Cl. 219—35)

This invention relates to a sterilizing apparatus in which the sterilization is effected by the action of heated air on the goods to be sterilized, for example medical and surgical instruments, bandages, rubber articles and other goods.

According to the invention the sterilization is carried out with the aid of a hermetically closable container provided with thermic external insulation and containing an electric heating element 10 for supplying the necessary heat. As the sterilizing chamber is hermetically closed only the heated air enclosed therein acts on the goods to be sterilized, which are placed in the chamber, the maximum temperature of the air being automatically 15 regulated. A detrimental effect upon the goods to be sterilized can consequently not take place as in all other methods of sterilizing.

The limitation to a maximum internal temperature according to the invention can be attained in 20 that the capacity of the electric heating element and its dimensioning is in a certain relation to the heat accumulating capacity or to the heat conductivity and to the thickness of the layer of insulation employed, and any excess of heat is led off to 25 the outer side through the insulation layer. If the apparatus is to be employed for different sterilizing temperatures, it is provided with an automatically operating thermo-regulator by which the current is switched off when a certain internal 30 temperature is reached.

For the purpose of increasing the heating effect and its uniform distribution over the whole of the interior of the container, this container is preferably provided with a polished metal lining, which 35 by reflection of the heat rays prevents any undesirable absorption of heat by the container wall, especially by its insulation.

The electric source of heat is advantageously fixed on the inner surface of one or more side walls 40 of the sterilizing chamber, preferably opposite the door. The heat rays are then directed towards the coldest portion of the sterilizing chamber which is evidently near the door.

Both the sterilizing apparatus and also the 45 source of heat may be foldably mounted in order that the source of heat may be employed in vertical or horizontal position. The device for actuating the same may be coupled with another device which during the folding over of the source of 50 heat positively changes its electric resistance and consequently its heating efficiency. The container is automatically adjusted to different working temperatures in each of its two positions of use.

Recesses may be provided in the sterilizing 55 chamber for accommodating the electric heating

element and receptacles for cooling media and the like. The apparatus, if cooling media, such as solidified carbon dioxide, are accommodated therein, can be used as an ice box, when the source of heat is switched out.

5

In order to accelerate the cooling of the container walls after the heat treatment has been terminated, when it is desired to change over the apparatus for cooling purposes, a cooling means, such as a water coil fed from any suitable source, 10 is preferably built into the insulating layer.

It is important for the sterilization, that all 15 possibility of oxidation is eliminated, for example in the case of metal articles to be sterilized. This is attained in a perfect manner according to the invention in that the oxygen of the imprisoned air is used up by the resistance wire of the electric source of heat. For this purpose the source of heat is so arranged that it acts directly on the air. The resistance wires are therefore situated in the 20 sterilizing chamber and only protected against damage and contact by a netting. The heating effect is also considerably increased by this arrangement of the resistance wires.

Hollow spaces or air spaces are preferably provided in the insulating layer for preventing any 25 effect of the external temperature.

The sterilizing apparatus is, according to the invention, fitted with a separate temperature regulator by means of which any alteration of the 30 desired temperature is prevented in the sterilizing chamber. This temperature regulator consists of an element expanding under heat and which at a certain temperature acts on a valve or the like so that cold air can flow into the chamber and 35 the excess of heat is discharged from the chamber. By inserting differently regulatable elements expanding under heat, it is possible to regulate to any desired maximum temperature.

The door of the apparatus is provided with 40 closing devices effecting hermetic closure.

The apparatus may also be employed as cooking apparatus besides for sterilization and cooling purposes.

Two embodiments of the invention are illustrated in the accompanying drawing, in which:—

Fig. 1 shows an apparatus in side elevation partly in section.

Fig. 2 is a top plan and part sectional view of Fig. 1.

Fig. 3 shows a modified form of construction in longitudinal section.

The outer casing 1 of the apparatus encloses an insulating layer 2, the exposed surface of which is lined with metal foil 3. An electric heat- 55

ing coil 5 is accommodated in a recess 4 in the wall of the container and separated from the interior of the container by a wire netting 6. Hinge plates 8 are slidably located between guide ribs 5 7 on the side wall and held in position by means of pins 10 engaging in slots 9 in the hinge plates 8. The container door 12 is carried on the other end of these hinge plates 8 by means of hinges 11. This door 12 also consists of an outer wall 1, 10 an insulating layer 2 and a polished metallic lining 3. The door 12 is provided with packings 13 hermetically fitting in the rebate 14 on the edge of the open side of the container when the door is closed. Turn-buckles 15 are foldably 15 mounted one on each side wall of the container and when the door is closed, they engage in corresponding forks 16 projecting laterally from the door. By tightening the wing nuts of the turn-buckles, the hinge plates 8 slide in their guides 7 and the door is tightly pressed into the rebate. The current leads, switches and the like and also 20 the control thermometer 17 are of usual construction.

According to Fig. 3 air chambers 25 are provided directly in the insulating layer 2 or in the wall 1 or 3. The door 12 can be swung downwards about hinges 11. All the edges of the door are bevelled. When being closed, the door, which has packings 13 on its edges, hermetically fits in 25 the rebate 14 provided with similar bevelled surfaces. A screw 18 projects from the rebate 14 and for locking the door engages a screw nut 19, the nut being actuated from the outer side of the door by means of a handle 20 rotatably mounted 30 therein. One or several such closing devices 18, 19, 20 may be provided at one or several points 35 of the apparatus.

For the continual automatic regulation of the desired temperature in the sterilizing chamber 40 the following arrangement is provided according to the invention:—

A temperature regulator consisting of an element 21 expansible under heat is fitted either 45 in any of the walls of the casing or, as shown in Fig. 3 in the door. This element is fitted in a guide 22 made of suitable material mounted in the door and fixed at 23 on the side adjacent the interior of the sterilizing chamber. The air imprisoned in the sterilizing chamber can thus 50 flow directly against this inner end of the element 21.

On the free end of the element 21 a valve 24 is mounted which, when the element 21 expands, 55 opens slightly so that cold air can flow into and the excess heat can be discharged from the chamber. The valve 24 again closes when the element 21 contracts. This procedure recurs continually and maintains a constant maximum temperature 60 in the sterilizing chamber independently of the external temperature and without switching in and out of the electric heating.

The place at which the expansible element is fitted and its construction may be chosen to suit the actual requirements.

65 The door may be provided with a known contact device which interrupts the current supply when the door is opened.

I claim:—

1. A sterilizing and cooking apparatus comprising in combination an outer casing adapted to be set up selectively on one of two adjacent sides, 70 a door on one end of said casing, an insulating

layer on the inner side of the walls of said casing and said door, said layer having a recess opposite said door, a metal foil lining said insulating layer to form a heating chamber and having an aperture registering with the recess in said insulating layer, an electric heating coil in the recesses in said insulating layer so that the heat rays are always directed towards the coolest portion of said chamber, and a wire netting over the aperture in said metal foil lining separating said electric heating coil from said heating chamber.

2. In a sterilizing and cooking apparatus as specified in claim 1, hinges secured to one edge of the door and each having a slotted plate, pins on said casing one engaging in the slot of each of said plates and adapted to hold said hinge plates in position on said casing, ribs on the outer side of said casing adapted to guide said hinge plates, forks on the outer side of said door projecting beyond two opposite edges thereof, and turn-buckles one on two opposite walls of said casing each turnbuckle adapted to engage one of said forks to pull said door tightly against said casing.

3. In a sterilizing and cooking apparatus as specified in claim 1, hinges secured to one edge of the door and each having a slotted plate, pins on said casing one engaging in the slot of each of said plates and adapted to hold said hinge plates in position on said casing, ribs on the outer side of said casing adapted to guide said hinge plates, forks on the outer side of said door projecting beyond two opposite edges thereof, turn-buckles one on two opposite walls of said casing each turnbuckle adapted to engage one of said forks to pull said door tightly against said casing, a rebate formed on the walls of said casing adjacent said door, and packings on the inner side of said door adapted, when the door is closed, to engage said rebate and form therewith a hermetic closure.

4. A sterilizing and cooking apparatus as specified in claim 1 in which the metal foil lining the inner side of the door is polished to split up and reflect the heat rays impinging thereon from the heating coil.

5. In a sterilizing and cooking apparatus as specified in claim 1, the walls of said casing bevelled at the end adjacent said door, and said door bevelled towards each edge to correspond with the bevelled portion of said casing walls, a rebate formed on the inner end of the bevelled portion of said casing walls, packing on the inner wall of said door adapted to bear against said rebate when the door is closed, said door having a hole near one of its edges, a screw forwardly 5 projecting from the rebate on the wall opposite said hinge and adapted to extend through said hole when the door is closed, and a screw nut in said hole adapted to engage said screw to press said door tightly against said casing, and a handle on said nut adapted to rotate the same.

6. In a cooking and sterilizing apparatus as specified in claim 1, a temperature regulator comprising an element expansible under heat mounted in said door, a guide carrying said element 64 and fixed to the inner side thereof, and a valve on the outer end of said element adapted when the temperature in said chamber reaches a predetermined maximum to open under the influence of the expanding element to ventilate said chamber.

MANFRED ABRAHAM.
